UNITED STATES PATENT OFFICE.

JOHN W. CHAMPION, OF COLORADO SPRINGS, COLORADO.

RAILWAY-TIE.

1,253,784.

Specification of Letters Patent.

Patented Jan. 15, 1918.

Application filed October 19, 1916. Serial No. 128,614.

To all whom it may concern:

Be it known that I, JOHN W. CHAMPION, citizen of the United States, residing at the city of Colorado Springs and State of Colorado, have invented certain new and useful Improvements in Railway-Ties; and I do declare the following to be a full, clear, and exact description of the invention, such as will enable others skilled in the art to which it appertains to make and use the same, reference being had to the accompanying drawings, and to the characters of reference marked thereon, which form a part of this specification.

10 The present invention relates to improvements in railway ties and pertains more particularly to ties made of rolled metal.

The invention has for its principal object to provide an improved form of metallic tie 20 which will properly adjust itself to the surface of the ballast or road bed and which will further provide a strong and durable support for the rails under the varying loads caused by the rolling stock.

25 A further object of the invention consists in forming the tie of two parts, namely, a base plate and a main rail supporting body portion. The first named part is so constructed as to engage the surface of the road bed and prevent creeping or lateral displacement. The second part is adapted to be resiliently supported on and attached to the base plate thereby providing for the necessary expansion resulting from the depression caused by heavy loads passing over the rails. To accomplish this result a single horizontal base plate is provided having its lower surface roughened or corrugated and its lateral edges bent upwardly to provide 40 tongues. The rail supporting body of the tie is formed in the shape of an inverted trough, having downwardly inclined sides, the lower edges of which are provided with flaring flanges adapted to enter the inner sides of the tongues of the base plate. An interlocking relation of the parts is thus provided which, however, permits of sufficient play to allow the main body portion of the tie to move vertically in relation to the 45 base plate.

With these and other objects in view the invention consists in the combination and arrangement of parts more fully set forth in the following specification, illustrated in

the accompanying drawing and more particularly pointed out in the appended claim.

55 In the drawings:

Figure 1 is a top plan view of one embodiment of the present invention.

Fig. 2 is a horizontal section taken on the line 2--2 of Fig. 1.

Fig. 3 is a transverse section taken on the line 3--3 of Fig. 1 drawn to a larger scale.

Fig. 4 is an enlarged fragmental view partly in section and partly in elevation of 65 the invention.

Fig. 5 is a fragmental perspective of a detail showing the fastening means of one end of the tie.

Fig. 6 is a sectional view showing one 70 manner of attaching a rail to a metallic tie according to the present invention.

Fig. 7 is a top plan view of the arrangement shown in Fig. 6, and

Fig. 8 is a detail of one of the rail fasten- 75 ing bolts detached.

Referring now to the drawing and particularly to Figs. 1 and 4, the tie comprises a base plate 5 and a body portion 6. The base is provided with a transversely corrugated surface 7 adapted to engage the ground ballast or road bed and is further provided at its opposite sides with upwardly bent portions 8 forming tongues, the purpose of which will hereinafter appear. The 80 rail supporting body member 6 is formed in the shape of an inverted trough or U and is provided with a pair of horizontally disposed depending, reinforcing webs 9 at approximately equal distances from its transverse center. The sides 10 of the member 6 incline outwardly and downwardly and terminate at their lower edges in angularly bent outwardly extending flanges 11 adapted, as shown in Figs. 3 and 5, to extend into 85 the tongues 8 formed at the sides of the base plate 5. It will be noted that in position of the parts shown in Fig. 3, which is assumed to be the normal position without any load, the flanges 11 do not extend clear into the recess formed by the tongues 8. In order to firmly clamp the parts in interlocking relation with each other and prevent sidewise movement of the parts the tongues 8 are slit 100 on a line 12 and the portion 13 is bent downwardly as shown in Fig. 5 contacting with the outer edge of the flange 11 of the mem-

ber 6. This is done at each end of the base plate 5 and at each side of the body portion 6 so there are for each tie four depressed lugs 13.

It will thus be seen that the rail supporting trough member 6 is firmly secured to the base plate 5 and that the slot and groove connections provided along its lower side edges are such that as a heavy load passes over the rails the member 6 is capable of being depressed and the expansion caused thereby is taken care of by a slight outward movement of the flanges 11 within the grooves formed by the tongues 8. The corrugated surface 15 of the base plate 5 grips the ground firmly and in cases where ballast composed of broken rocks or boulders is used the roughened surface will prevent any side displacement of the base plate in relation to the road 20 way.

Referring to Figs. 6, 7 and 8, one form of the rail fastening means is shown. The upper surface of the rail supporting body portion of the tie 6 is provided with pairs of slotted openings 14. Each opening comprises a longitudinal slot having a cylindrical opening communicating therewith and formed nearer one end than the other. The base plate of a rail 15 is placed transversely across the tie member 6 as shown in Fig. 6 and there clamped in position by means of a fastening device. A bolt 16 such as shown in Fig. 8 is provided with a cylindrical screw threaded stem and a flattened head. A portion of the bolt stem adjacent the head is also flattened and is of sufficient width to enter the slotted opening 14. The head of the bolt is inserted into the opening 14 and the bolt is then given a quarter turn, the cylindrical portion of the stem being slightly larger in diameter than the width of the flattened portion the bolt is retained and prevented from dropping downwardly.

A clamping member 17 having a portion adapted to extend downwardly into the slot 14 is then applied over the projecting stem of the bolt. This member 17 is also provided with a forward curved extension lug which overlaps and firmly engages the upper surface of the flange of the base of the rail. 50 By applying the nut 18 to the thread of the bolt and screwing the nut down firmly against member 17, the clamping devices are firmly secured in place. It will be noted that the cylindrical portion of the stem of 55 the bolt 16 together with the downwardly extending portion of the clamping device 17 completely fill the space between the outer edge of the rail flange and the further end of the slot 14 hence there can be no rattling 60 or loosening of the parts. The fastening devices are so constructed that they would not become displaced even though the nut 18 were not applied to the upper threads of the bolt 16. The only manner in which the 65 clamping devices 17 can be removed is by raising them vertically upward until they become disengaged from the openings 14.

Having described my invention what I claim is:

A railway tie comprising a base plate provided with upturned edges and a body portion having outwardly projecting flanges engaging said upturned edges in interlocking relation, the upturned edges being slit adjacent their ends and the end portions bent downwardly to respectively engage the end edges of the said flanges to prevent sidewise movement of the parts.

In testimony whereof I affix my signature, in presence of two witnesses.

JOHN W. CHAMPION.

Witnesses:

HELEN A. VILLEMAGNE,
CHARLES E. PARSONS.
